Primary Examiner — Samantha Q Lawrence(74) *Attorney, Agent, or Firm* — Oyen Wiggs Green & Mutala LLP(57) **CLAIM**

The ornamental design for a solar post cap as shown and described.

DESCRIPTION

FIG. 1 is a top perspective view of the solar post cap; FIG. 2 is a bottom perspective view of the solar post cap of FIG. 1;

FIG. 3 is a front elevational view of the solar post cap of FIG. 1, the rear elevational view being identical;

FIG. 4 is a left side elevational view of the solar post cap of FIG. 1, the right side elevational view being identical;

FIG. 5 is a top plan view of the solar post cap of FIG. 1; and,

(Continued)

FIG. 6 is a bottom plan view of the solar post cap of FIG.

1.

The areas indicated by thin diagonal lines represent translucency.

1 Claim, 5 Drawing Sheets
